RECOVERY OF CYCLOTRIMETHYLENE-
TRINITRAMINE

Willard de C. Crater, Newark, Del., assignor to
Hercules Powder Company, Wilmington, Del.,
a corporation of Delaware

No Drawing. Application April 10, 1948,
Serial No. 20,362

4 Claims. (Cl. 260—248)

2

1 This invention relates in general to a process for the recovery of cyclotrimethylenetrinitramine, hereinafter referred to as cyclonite, from explosive mixtures and more particularly to a process for the recovery of cyclonite from mixtures with such substances as trinitrotoluene, tetryl, nitrocellulose, waxes, and various plasticizers.

Cyclonite is a white crystalline substance with a melting point of about 202° to 204° C., depending on the method of manufacture, and is one of the most powerful of modern high explosives. While its primary use is in military explosive compositions, relatively small, but nevertheless substantial quantities of cyclonite are needed in the preparation of various smokeless powders and special industrial explosives. Since cyclonite is not being manufactured in quantity at the present time, the limited demand for cyclonite must be satisfied by its recovery from the surplus military explosives which contain it.

It is known to the art to separate cyclonite from explosive mixtures by dissolving the entire mixture in a common solvent such as acetone and then precipitating the various components from solution by agitating and adding water. This separation depends upon the difference in respective solubility of the components in the dilute solvent. This process has utility where it has not been necessary to obtain cyclonite of a high degree of purity. The process is unsatisfactory, however, when highly pure yields are desired without the necessity of subsequently refining the product. This is true because it is an inherent defect of such a process that small amounts of the components of the mixture, which separate either before or after the desired fraction, will be carried over with and contaminate the desired product. For example, if cyclonite and trinitrotoluene are dissolved in acetone and water is added, the cyclonite will precipitate in a mother liquor which is a concentrated solution of trinitrotoluene in acetone and water. The crystals will therefore contain substantial amounts of this mother liquid which washing will not remove. To purify it, it is therefore necessary to recrystallize until the necessary purity is achieved. This extra manipulation is undesirable from the standpoint of both economy and safety.

It has been found that the cyclonite contained in the available military explosive compositions has the desired particle size for use in propellant powder. It is therefore highly desirable to recover the cyclonite in such a manner that the particle size will be retained. This obviously

cannot be done if the cyclonite is itself dissolved according to the prior art processes. When the cyclonite is so dissolved, it is exceedingly difficult to recrystallize to the desired particle size.

5 Now in accordance with the present invention it has been found that cyclonite may be recovered from explosive compositions in excellent yields, in a highly pure state, and in the desired particle size.

10 Generally described, the invention comprises the treatment of an explosive composition containing cyclonite with a solvent or mixture of solvents in which the cyclonite is substantially insoluble and the remaining components are soluble. Solvents such as chloroform, ethyl ether, mixtures of ethyl ether and ethyl alcohol, and mixtures of ethyl ether, ethyl alcohol and chloroform may be employed. Although acetone alone is an excellent solvent for cyclonite, it has been found that when acetone is mixed with the proper proportions of an aliphatic alcohol having from 2 to 4 carbon atoms, namely, ethyl, propyl, and isopropyl alcohols, very little cyclonite is dissolved and such mixtures are excellent solvents for the other ingredients of certain of the explosive mixtures containing cyclonite. However, of the above solvents and mixtures of solvents, a mixture of ethyl ether and ethyl alcohol has been found preferable.

15 The recovery process essentially comprises placing the explosive composition in a suitable vessel, adding the desired solvent or mixture of solvents, and agitating the mixture at temperatures which may vary from room temperature to the reflux temperature of the solvent. The cyclonite retains its crystalline form while the remaining components go into solution. Separation of the cyclonite from the solvent and dissolved materials may be achieved by filtration, centrifuging, or other suitable procedure. The cyclonite is then washed; preferably with a small portion of solvent, which may be used in subsequent runs. The recovered cyclonite is now in a highly pure state and, if desired, may be removed directly from the filter and incorporated in the explosive or propellant for which it is required.

20 Having now generally disclosed the nature of the present invention, the following examples are given for purposes of illustration. Unless otherwise indicated, the specified amounts of explosive mixtures and solvent were placed in a vessel equipped with heating jacket, an agitator and a reflux condenser. Unless otherwise indicated, each charge was agitated at reflux

temperature for 20 minutes. All parts are by weight.

vent and solvent amounts are shown in the following table:

Solvent	Wt. Rinse	Recovered Cyclonite		
		Wt.	Per cent	Remarks
1:2 Ether/Alc.....	100	95	36.5	94.8 White, free-flowing.
Do. ¹	175	100	36.3	94.3 Do.
Do. ¹	300	100	36.0	93.5 Do.

¹ Agitated 30 minutes instead of 20.

Example 1

Cyclonite was recovered from 50 gram portions of an explosive mixture containing 60% cyclonite and 40% TNT. Type and amount of solvent and results are shown in the table below:

Solvent	Wt. Rinse	Recovered Cyclonite		
		Wt.	Per cent	Remarks
Chloroform.....	200	100	31.1	103.7 Yellow cast.
Do.....	250	100	28.6	95.3 White, free-flowing.
1:2 ether/alcohol.....	200	100	37.0	123.3
Do.....	250	100	27.2	90.7 Do.
Do.....	300	100	29.6	98.7 Do.

Example 2

Cyclonite was recovered from 50 gram portions of a plastic explosive containing about 88%

Cyclonite was recovered from 500 gram portions of an explosive containing about 75% of cyclonite plasticized with a mixture of mono-, di-, and trinitrotoluenes; tetryl, nitrocellulose

Example 5

and a solvent. The following table shows the solvent, the amounts of solvent used and the results obtained:

Alcohol	Acetone Wt. g.	Wash Solvent			Cyclonite Recovered		
		Type	Wt. g.	Alcohol	Acetone	Wt.	Per cent
Ethyl.....	500	500	250	250	345	89	White, free-flowing.
Do.....	250	250	375	125	360	93	Do.
Do.....	780	220	390	110	382	93	Do.
Isopropyl.....	250	250	375	125	355	92	Do.

¹ Some cyclonite was lost due to slight solubility in the solvent mixture. However, yields can be improved by the recycling of the solvent.

cyclonite mixed with petrolatum or other waxes. Type and amount of solvent and results are presented in the following table:

Example 6

A larger quantity of cyclonite was produced on plant scale by the following procedure: 18

Solvent	Wt. Rinse	Recovered Cyclonite		
		Wt.	Per cent	Remarks
Chloroform.....	300	100	42.6	96.5 Slight tint.
Do.....	350	100	44.6	101.0 Do.
Do.....	400	100	43.9	99.4 White, free-flowing.
1:1:1 ether/alcohol/chloroform.....	200	100	44.2	100.0 Slight tint.

Example 3

Cyclonite was recovered from 50 gram portions of an explosive containing about 80% of cyclonite which had been plasticized with a mixture of mono-, di-, and trinitrotoluenes; nitrocellulose and a solvent. The following table shows type and amount of solvent used and the results of the treatment:

pounds of the explosive treated in Example 4 were placed in a vessel equipped with an agitator. Thirty-six pounds of a 2:1 mixture of ether-alcohol was added and the contents agitated for one-half hour at room temperature. The cyclonite was allowed to settle, the mother liquor was decanted, the cyclonite was washed with fresh solvent and filtered. All of the wash

Solvent	Wt. Rinse	Recovered Cyclonite		
		Wt.	Per cent	Remarks
1:2 Ether/Alc.....	250	100	39.2	96.8 White.
Do.....	200	100	40.4	100.0 Slight tint.
1:1 Ether/Alc.....	200	100	40.4	100.0 White, free-flowing.

Example 4

Cyclonite was recovered from an explosive containing about 75% of cyclonite plasticized with a mixture of mono-, di-, and trinitrotoluenes; tetryl, nitrocellulose and a solvent. Results, sol-

liquor and part of the mother liquor was recycled to form the extracting medium for the following batch. The yield from this process averaged about 98% of white, free-flowing crystals having a melting point of about 204.5° C.

and no nitro body odor. The following table shows the results of four typical runs:

Ether/Alcohol		Wt. Rinse	Recovered Cyclonite		
Mother Liquor	Wash Liquor		2:1 E/Ale.	Wt. Dry	Per Cent
19½	16½		18	13.54	96.4
15	21		18	13.76	98.1
15	21		18	13.86	98.7
15	21		18	13.90	99.0

The foregoing examples serve to illustrate my process, but the process is not limited by the ratios used or the solvents used. Any solvent or mixtures of solvents may be employed in which the cyclonite is substantially insoluble, but which are solvents for the other ingredients of the composition to be treated for the recovery of cyclonite. Furthermore, the solvent to be used for the recovery of cyclonite from explosive compositions by my process depends on the ingredients of the composition. That is, these compositions vary and the solvent selected should be one which most readily dissolves the ingredients to be removed, and which is substantially a nonsolvent for cyclonite.

The above examples clearly illustrate that highly pure cyclonite may be recovered from military explosive in good yields. The degree of purity may be readily controlled by the particular solvent, the amount of solvent, the agitation time, and the temperatures employed. The highest possible purity is of course attained when all of the components other than the cyclonite are completely dissolved leaving the cyclonite crystals in the same condition as when they were incorporated in the mixture under treatment. If this is not done, the crystals will be externally contaminated to a relative degree and will be characterized by discoloration, odor, difference in melting points, etc.

It is generally preferred to carry out the extraction process at the reflux temperature of the solvent employed because less solvent is required at that temperature than at lower temperatures. However, a comparison of Examples 4 and 6 illustrates that by recycling the wash liquor and a portion of the mother liquor, high purity and efficiency can still be achieved at room temperatures without too great an increase in solvent cost and extraction time.

The vessel employed may be of any suitable type equipped with agitating means, a heating means, and a reflux condenser. Since all of the preferred solvents boil substantially below 100° C., adequate heating can be accomplished by employing a jacketed vessel and circulating water through the jacket at the desired temperature.

The components of the explosive mixtures other than the cyclonite may be recovered or disposed of as circumstances warrant. The used solvents may be mixed with water and recovered for re-use by rectification.

What I claim and desire to protect by Letters Patent is:

1. A process for the recovery of cyclonite crystals from explosive mixtures containing cyclonite crystals and at least one of the group consisting of mononitrotoluene, dinitrotoluene, trinitrotoluene, nitrocellulose, and tetryl which

comprises mixing together the explosive mixture and a member of the group of solvent mixtures consisting of a mixture of ethyl ether and ethyl alcohol, a mixture of ethyl ether, ethyl alcohol, and chloroform, and a mixture of acetone with an aliphatic alcohol having from 2 to 4 carbon atoms; agitating the mixture of explosive and solvent at a temperature of from room temperature to the reflux temperature of the solvent until substantially all of the explosive mixture except the cyclonite crystals is in solution; and separating the cyclonite crystals from the solution.

2. A process for the recovery of cyclonite crystals from explosive mixtures containing cyclonite crystals and at least one of the group consisting of mononitrotoluene, dinitrotoluene, trinitrotoluene, nitrocellulose, and tetryl which comprises mixing together the explosive mixture and a solvent mixture of ethyl ether and ethyl alcohol; agitating the mixture of explosive and the solvent mixture at a temperature of from room temperature to the reflux temperature of the solvent until substantially all of the explosive mixture except the cyclonite crystals is in solution; and separating the cyclonite crystals from the solution.

3. A process for the recovery of cyclonite crystals from explosive mixtures containing cyclonite crystals and at least one of the group consisting of mononitrotoluene, dinitrotoluene, trinitrotoluene, nitrocellulose, and tetryl which comprises mixing together the explosive mixture and a solvent mixture of ethyl ether, ethyl alcohol and chloroform; agitating the mixture of explosive and the solvent mixture at a temperature of from room temperature to the reflux temperature of the solvent until substantially all of the explosive mixture except the cyclonite crystals is in solution; and separating the cyclonite crystals from the solution.

4. A process for the recovery of cyclonite crystals from explosive mixtures containing cyclonite crystals and at least one of the group consisting of mononitrotoluene, dinitrotoluene, trinitrotoluene, nitrocellulose, and tetryl which comprises mixing together the explosive mixture and a solvent mixture of acetone with an aliphatic alcohol having from 2 to 4 carbon atoms; agitating the mixture of explosive and the solvent mixture at a temperature of from room temperature to the reflux temperature of the solvent until substantially all of the explosive mixture except the cyclonite crystals is in solution; and separating the cyclonite crystals from the solution.
